(57) **CLAIM**

I claim the ornamental design for a sealable stackable container, as shown and described.

DESCRIPTION

FIG. 1 is an exploded top perspective view of a sealable stackable container, showing my new design;

FIG. 2 is a top perspective view thereof;

FIG. 3 is an exploded front elevational view thereof;

FIG. 4 is an exploded rear elevational view thereof;

FIG. 5 is an exploded left-side elevational view thereof;

FIG. 6 is an exploded right-side elevational view thereof;

FIG. 7 is an exploded top plan view thereof;

FIG. 8 is an exploded bottom plan view thereof;

FIG. 9 is an exploded bottom perspective view thereof; and

FIG. 10 is a cross-sectional view of a lid of the design, taken along line **10-10** of FIG. 7; and,

FIG. 11 is a cross-sectional view of a container of the design, taken along line **11-11** of FIG. 8.

The broken lines showing a removable container divider and additional container bases in FIG. 1 depict environmental matter and form no part of the claimed design.
